UNITED STATES PATENT OFFICE.

JENS A. PAASCHE, OF CHICAGO, ILLINOIS.

AIR-BRUSH.

1,125,873.

Specification of Letters Patent.

Patented Jan. 16, 1915.

Application filed April 24, 1909. Serial No. 482,012.

To all whom it may concern:

Be it known that I, JENS A. PAASCHE, a citizen of the United States, residing at Chicago, in the county of Cook and State 5 of Illinois, have invented certain new and useful Improvements in Air-Brushes, of which the following is a specification.

The object of this invention is to provide an air brush of improved construction, and 10 a special object is to produce a novel and improved color discharge means.

In some of the air brushes heretofore produced, a needle and surrounding nozzle have been employed to control the discharge 15 of color, the color flowing through the nozzle around the needle. I have found that superior results are obtainable by providing a needle which is itself adapted to convey the color, the discharge of the color 20 being controlled by a nozzle as will be fully described. I believe myself to be the first to produce an air brush having a needle adapted to convey color.

In the accompanying drawings, Figure 25 1 is a top plan view of an air brush embodying the features of my invention, a portion 25 of the body being broken away. Fig. 2 is a section on line 2-2 of Fig. 1. Fig. 3 is a horizontal section through the mechanism 30 of the brush. Figs. 4 and 5 are sectional views similar to that of Fig. 3, but on a greatly enlarged scale. Fig. 4 showing the color discharge closed, and Fig. 5 showing said discharge opened. Fig. 6 is a section 35 on line 6-6 of Fig. 2. Fig. 7 is a section on line 7-7 of Fig. 2. Fig. 8 is a sectional detail view of a means for preventing the operating plunger from turning accidentally.

The embodiment of the invention which 40 has been selected for illustration comprises a body consisting of a stem 1 and an attached handle 2. The stem 1 has a tapering forward end. In the forward portion of the stem 1 is an air passage 3 extending to 45 the air-discharge orifice 4^a of the tip or nozzle 4. The latter has an annular flaring flange 5 which serves to protect the needle, to be hereinafter described, from accidental injury.

50 The air valve is situated in a position to be operated by the index finger when the brush is held in pencil fashion between the fingers of the hand. The casing of said air valve comprises a cylindrical block 6 fixed 55 in an opening 7 in the stem 1. The cylindrical block is threaded to admit a tubular

stem 8 on the section 9 of the valve casing. The air passage 3 extends through the casing-sections 6 and 9 into communication with the bore of the tubular stem 8. Within the casing-section 9 is a valve seat 10 upon which a valve member 11 is arranged to seat. A coiled spring 12 interposed between said valve member and a spring-seat 13 threaded into the lower end of the casing-section 9 tends to hold the valve member 11 against its seat. A flexible air tube (not herein shown) may be attached to the lower end of the casing-section 9, the spring-seat 13 being perforated as at 14 to admit the pressure air to the valve casing. The valve member 11 is provided with a stem 15 which extends into an axial opening in the lower end of a plunger 16, said plunger being vertically slidable within the tubular stem 8. When the plunger 16 is depressed, the valve member 11 is unseated and pressure air permitted to flow through the passage 3 to the air-discharge orifice 4^a.

The color-discharge devices comprise a sleeve 17 supported by a stud 18 upon the stem 1 and fixed in said stud by a set screw 19. The axis of the sleeve 17 extends at an angle to the axis of the air-nozzle 4. A needle 20 is supported stationarily and 50 adjustably in the sleeve 17 by suitable means, such as a screw 21 engaging screw-threads in the rear end of the sleeve 17, said screw having a knurled flange 22 by means of which it may be rotated to adjust the needle 20 longitudinally of the sleeve 17. The needle 20 is fixed to the screw 21 in any suitable way, as by a screw-thread connection. The larger part of the needle is cylindrical, the forward end 20^a thereof being 55 tapering or conical.

The needle 20 is surrounded by a nozzle 23 having a cylindrical bore to receive the needle 20, said bore having a tapering forward end to fit upon the tapered end 20^a of the needle. The nozzle 23 is slidable within an opening 24 in the forward end of the sleeve 17, and when projected into its forward position the tip of said nozzle extends substantially to the axis of the air-nozzle 4.

In the rear end of the screw 21 is an opening 25 which may be slightly tapered to receive the end of the delivery tube 26 of a color bottle or cup 27. The opening 25 110 communicates with a duct 28 extending longitudinally of the needle 20 and opening at

29 upon the periphery of the tapered portion 20^a of said needle. It will be seen that when the needle 23 is in such position that its forward end fits snugly upon the tapered portion 20^a, the flow of color through the opening 29 is cut off, and that when said nozzle is slid along the needle until the walls of the taper portion of the bore of said sleeve are out of contact with the taper portion 20^a, the pigment may flow through the opening 29 and through the annular space between the forward end of the nozzle.

The means herein shown for reciprocating the nozzle 23 to open and close the color discharge comprises a spring 30 surrounding said nozzle and interposed between a shoulder 31 in the sleeve 17 and one side of an annular flange 32 on the nozzle. Said spring tends to move the nozzle to cut off the flow of color. The nozzle 23 is moved to open the color discharge by a plunger 33 slidably mounted in an opening 34 in the stem 1. Upon the forward end of the plunger 33 is a head 35 arranged to bear upon the flange 32. One side of the head 35 is cut away, as shown, so that said head may be rotated out of engagement with the flange 32 to permit of withdrawing the sleeve 17 from the stud 18. The plunger 33 may be held against accidental rotation by any suitable means, such as a screw 33^a mounted in the stem 1 and arranged to contact lightly a flattened surface 33^b upon the plunger 33. An arm 36 is pivotally mounted in the stem 1 upon a pin 37 and lies in contact with the rear end of the plunger 33. In order to lessen the area of contact and thereby reduce friction, the portion of the arm 36 in contact with the plunger may be in the form of a rib 38.

Upon the upper end of the plunger 16 is pivotally mounted a lever 39, the upper end of which carries a portion 40 for engagement by the tip of the index finger of the operator. The lower end of said lever lies behind the arm 36, the latter being made relatively broad so that the lever may remain in contact with the arm during the reciprocatory movements of the plunger 16. The normal or initial pivotal position of the lever 39 is determined by an adjusting screw 41 seated in the plunger 16. The extent to which the plunger 16 may be depressed is limited by an adjusting screw 42 seated in the stem 1, the knurled head 43 of which screw is arranged to be engaged by a portion moving with said plunger, as, for example, the pivot pin 44 of the lever 39. The lower portion of the lever 39 extends through a slot 45 in the stem 1, the lower extremity of said lever being enlarged as at 46 to prevent accidental withdrawal of the lever through said slot. The rear portion 47 of the slot is enlarged to permit the en-

largement 46 to pass through the slot in assembling and disassembling the parts.

In use, the brush is held by the fingers of the right hand in pencil fashion, the discharge of air and color being controlled by operating the lever 39 with the index finger. When the portion 40 is depressed so as to unseat the disk 11 air flows through the passage 3 to the nozzle 4. If now the operator tilts the portion 40 rearwardly the nozzle 23 will be slid forwardly to uncover the opening 29, whereupon the suction of the air blast passing the point of the needle and the tip of the nozzle 23 causes a flow of color from the bottle 27 through the tube 28, the needle 20 and the annular space between the forward ends of the needle and the nozzle 23. It will be seen that the nozzle 23 conducts the pigment to the line of the current of air, the air blast atomizing the pigment and carrying it onto the surface to be painted. The strength of the air current and the amount of color discharged may be varied by depressing and tilting the lever 39 to varying extents. The needle 20 may be adjusted longitudinally into proper relation with the air current by rotating the screw 21. The screw 41 is ordinarily adjusted so that when the air valve is opened the color discharge will be open sufficiently to make a line. Said screw also permits of taking up wear on the needle, by permitting the spring 30 to push the nozzle 23 further rearward. When stippling is to be done the screw 42 is adjusted so that the desired amount of air will be discharged when the plunger is depressed so as to bring the pin 44 in contact with the screw-head 43. The less air admitted, the coarser the stipple produced.

I would have it understood that the invention is not limited to the details of construction herein set forth, as many modifications will occur to persons skilled in the art.

I claim as my invention:

1. In an air brush, a needle having an internal passage-way terminating at its forward end short of the forward end of the needle, and a nozzle surrounding said needle and adapted to control the discharge of fluid from said passage-way.

2. In an air brush, a needle tapered at its forward end and having an internal passage-way terminating on the tapered surface short of the forward end of the needle, and a nozzle surrounding said needle and having an internally tapered portion to fit against the tapered end of said needle.

3. In an air brush, in combination, a needle adapted to convey color, a nozzle surrounding said needle and adapted to control the flow of color; said elements being movable with relation to each other; and an air nozzle.

4. In an air brush, in combination, a needle adapted to convey color; a nozzle adapted to control the discharge of color, said nozzle surrounding said needle and being slidable with reference thereto; means for sliding one of said elements with reference to the other; and an air nozzle.
5. In an air brush, in combination, an air nozzle; a hollow needle adapted to convey color to its forward portion, said needle extending at an angle with the air nozzle; and a nozzle slidable longitudinally of the needle and adapted to control the flow of color.
6. In an air brush, in combination, an air nozzle; and color discharge means comprising a needle having an opening longitudinally thereof adapted to convey color, said opening terminating in the surface of said needle at a point short of the forward end thereof, and a nozzle slidable with reference to said needle and arranged to control the color discharge.
7. In an air brush, in combination, an air nozzle; a needle adapted to convey color to its forward portion; said needle extending at an angle with the air nozzle; a nozzle slidable longitudinally of the needle and adapted to control the flow of color; means tending to hold said second mentioned nozzle in position to cut off the color supply; and means for moving said second mentioned nozzle to permit the discharge of color.
8. In an air brush, in combination, an air nozzle; means for controlling the admission of air to said nozzle; color discharge means comprising a needle adapted to convey color to its forward portion; said needle extending at an angle with the axis of said air nozzle; a nozzle surrounding said needle and adapted to control the flow of color, said second mentioned nozzle and said needle having a relative sliding movement; and a single means for controlling said color discharge means and said air supply controlling means.
9. In an air brush, in combination, an air nozzle; an air valve in communication with said nozzle; a needle adapted to convey color to its forward portion, said needle extending at an angle with the air nozzle; a nozzle slidable longitudinally of the needle and adapted to control the flow of color; and a finger-lever and connections for controlling said last mentioned nozzle and the air valve.
10. In an air brush, in combination, a body; air discharge means a sleeve carried by said body; a needle mounted in said sleeve and having an opening longitudinally thereof adapted to convey color, said opening terminating at the surface of the needle at a point short of the forward end thereof, the forward end of the needle being tapered; a nozzle mounted in said sleeve, said nozzle surrounding said needle and being slidable with reference thereto, the forward
- end of said nozzle being internally tapered to fit the tapered end of the needle; means tending to hold said tapered portions in contact; and means for moving said portions out of contact to permit the flow of color through said needle and said nozzle.
11. In an air brush, in combination; a body; a stud on said body; a sleeve movably mounted in said stud; a member having an adjustable connection with the rear end of said sleeve; a needle carried by said member, said needle being adapted to convey color to its forward portion; a nozzle surrounding said needle, and slidable in the forward end of said sleeve; said nozzle being adapted to control the discharge of color; and an air nozzle.
12. In an air brush, in combination, a body; a stud on said body; a sleeve movably mounted in said stud; a hollow member having a screw thread connection with the rear end of said sleeve; a needle fixed in said member and having an opening longitudinally thereof adapted to convey color, said opening communicating with the opening in said member and terminating at the surface of the needle at a point short of the forward end thereof, the forward end of said needle being tapered; a nozzle mounted in said sleeve, said nozzle surrounding said needle and being slidable with reference thereto, the forward end of said nozzle being internally tapered to fit the tapered end of the needle, said nozzle being arranged to cut off the color when its tapered portion contacts the tapered end of said needle; and an air nozzle on said body.
13. In an air brush, in combination, a body; air discharge means; and color discharge means comprising a needle adapted to convey color to its forward portion; a nozzle slidably mounted on said needle and arranged to control the color supply; said nozzle having a shoulder thereon; means engaging said shoulder tending to hold said nozzle in position to cut off the discharge of color; a rod slidable in said body, said rod being arranged to engage the shoulder on said nozzle; and a finger lever and connections for moving said rod into position to permit the discharge of color.
14. In an air brush, in combination, a body; air discharge means thereon, a lug on said body; a sleeve adjustably mounted in said lug; a member adjustably secured to the rear end of said sleeve, said member having an opening therein; a needle fixed to said member, said needle having an opening communicating with the opening in said member, the opening in said needle terminating at the surface of said needle at a point short of the forward end thereof; a nozzle slidable in said sleeve and on said needle, said nozzle being arranged to control the discharge of color from said needle; a

- shoulder on said nozzle; a spring in said sleeve bearing against said shoulder and tending to hold said nozzle in position to cut off the color discharge; a rod slidably mounted in said body, and engaging said shoulder; and a finger lever arranged to move said rod into position to permit the discharge of color.
15. In an air brush, in combination, a body; a lug on said body; a sleeve adjustably mounted in said lug; means for fixing said sleeve in adjusted positions; a member having a screw thread connection with the rear end of said sleeve, said member having an opening therethrough; a needle fixed to said member; said needle having an opening coinciding with the opening in said member, the opening in said needle terminating at the surface of said needle at a point short of the forward end thereof, the forward end of said needle being tapered; a nozzle slidably in the forward end of said sleeve, said nozzle surrounding said needle and being slidable thereon; the forward end of said nozzle being internally tapered to fit the tapered portion of said needle; a shoulder on said nozzle; a coiled spring lying between one end of said sleeve and said shoulder; a rod slidably mounted in said body and adapted to engage said shoulder; an arm pivotally mounted in said body and arranged to engage said rod; an air nozzle; an air valve in communication with said nozzle, said valve having a stem; and a finger lever pivotally mounted on said stem and arranged to engage said pivoted arm.
16. In an air brush, a nozzle, and a needle within said nozzle, said needle having an internal passage-way adapted to convey fluid, said passage-way terminating at its forward end short of the forward end of the needle, the needle having a portion at its extreme forward end adapted to close the discharge end of said nozzle.
17. In an air brush, a nozzle, and a needle fitting in said nozzle and having its forward end arranged to close the discharge end of the nozzle, said needle having a longitudinal internal passage-way adapted to convey fluid and terminating rearwardly of said closing portion of the needle the fluid being discharged between the exterior surface of the needle and the interior surface of the nozzle.
18. In an air brush, a sleeve, a nozzle lying within said sleeve and being slidably mounted in the forward end of the sleeve, and a needle mounted in the rear end of the sleeve and being adapted to convey fluid to its forward portion, said nozzle being arranged to control the discharge of the fluid.
19. In an air brush, a member having a passage-way therethrough, one end of the passage-way being adapted to receive the conduit of a color receptacle, a needle mounted in the other end of said member and having a longitudinal opening communicating with said passage-way, and a nozzle slidably mounted on said needle and arranged to control the discharge of color through said opening.
20. In an air brush, a sleeve, a member mounted in the rear end of said sleeve and having a passage-way therethrough, one end of the passage-way being adapted to receive a conduit of a color receptacle, a needle mounted on said member and having a longitudinal opening communicating with said passage-way and adapted to convey color, and a nozzle surrounding said needle and slidably mounted in the forward end of said sleeve for controlling the discharge of color through the needle.
21. In an air brush, a needle having a tapered forward end and having a longitudinal internal passage-way running from its rear end and terminating upon the tapered surface at its forward end, and a nozzle surrounding said needle and having an internally tapered portion to fit against the tapered forward end of the needle, the nozzle fitting snugly on the needle rearwardly of said tapered surfaces, the nozzle and needle being movable longitudinally with relation to each other to separate said tapered surfaces and provide an annular chamber from which the color is discharged.

JENS A. PAASCHE.
